UNITED STATES PATENT OFFICE

134,941

DESIGN FOR A SHOPPER'S CART

William Hansen, Chicago, Ill.

Application May 4, 1942, Serial No. 106,783

Term of patent 3½ years

To all whom it may concern:

Be it known that I, William Hansen, a citizen of the United States, residing at Chicago, in the county of Cook and State of Illinois, have invented a new, original, and ornamental Design for a Shopper's Cart, of which the following is a specification, reference being had to the accompanying drawing, forming a part thereof.

Fig. 2 is a side elevational view of the cart;

Fig. 3 is a rear elevational view thereof.

I claim:

The ornamental design for a shopper's cart, substantially as shown.

WILLIAM HANSEN.
